US00D627720S

(12) **United States Design Patent**
DuMelle et al.

(10) **Patent No.:** **US D627,720 S**
(45) **Date of Patent:** **** Nov. 23, 2010**

(54) **POWER INVERTER**

(75) Inventors: **Barbara Margaret DuMelle**, Niles, IL (US); **Christopher Michael Kubik**, Chicago, IL (US); **Patrick J. Clarke**, St. Charles, IL (US); **Samuel Weisbard**, Highland Park, IL (US); **Joseph J. Zenkus**, Lake in the Hills, IL (US); **Mark Kurth**, Chicago, IL (US); **Timothy Payne**, Chicago, IL (US); **Adam Callif**, Chicago, IL (US)

(73) Assignee: **Schumacher Electric Corporation**, Mt. Prospect, IL (US)

(**) Term: **14 Years**

(21) Appl. No.: **29/354,897**

(22) Filed: **Jan. 29, 2010**

(51) LOC (9) Cl. **13-02**

(52) U.S. Cl. **D13/110**

(57) **CLAIM**

The ornamental design for the power inverter, as shown and described.

DESCRIPTION

FIG. 1 is a bottom isometric view of a power inverter showing our new design.

FIG. 2 is a top isometric view of the power inverter illustrated in FIG. 1.

FIG. 3 is a bottom plan view of the power inverter illustrated in FIG. 1.

FIG. 4 is a front elevation view of the power inverter illustrated in FIG. 1.

FIG. 5 is a right side elevation view of the power inverter illustrated in FIG. 1.

FIG. 6 is a rear elevation view of the power inverter illustrated in FIG. 1; and,

FIG. 7 is a top plan view of the power inverter illustrated in FIG. 1.

The broken lines shown are for illustrative purposes only and form no part of the claimed design.
